UNITED STATES PATENT OFFICE.

HARRY R. COWAN, OF CHICAGO, ILLINOIS.

CALCULATING AND PRINTING MACHINE.

1,077,220.

Specification of Letters Patent. Patented Oct. 28, 1913.

Application filed July 27, 1908. Serial No. 445,475.

To all whom it may concern:

Be it known that I, HARRY R. COWAN, a citizen of the United States, and a resident of Chicago, county of Cook, and State of Illinois, have invented certain new and useful Improvements in Calculating and Printing Machines, of which the following is a specification:

The invention relates to certain new and useful improvements in machines for adding and subtracting and for printing lines of numerals, and seeks to provide an apparatus of compact, inexpensive and simple structure, which may be conveniently used by accountants to enter columns of numerals in books or upon sales sheets, and to add and subtract the lines of numbers to ascertain their totals and differences.

While the improved machine may be held stationary and print upon paper fed beneath it, or may be mounted on rails to slide over the book or paper whereon the numbers are to be printed, it is preferably made of light construction, so that it can be readily moved by hand to print in different places and make entries wherever desired on books, sales sheets and the like.

With these and other objects in view, as will presently appear, the invention consists in the features of improvement hereinafter set forth, and more particularly pointed out in the appended claims.

In the drawings, which illustrate the present preferred embodiment of my invention, Figure 1 is a view in transverse section thereof on the line 1—1 of Fig. 2. Fig. 2 is a view in longitudinal section on the line 2—2 of Fig. 1. Fig. 3 is a view in front elevation of the machine. Fig. 4 is a section through the machine on the line 4—4 of Fig. 2 looking in the direction of the arrows 4. Fig. 5 is a detail section on the line 'a—a of Fig. 2, looking in the direction of the arrows 5. Fig. 6 is a detail section on the line 6—6 of Fig. 2. Figs. 7 and 8 are detail views looking in the direction of the arrows 7 in Fig. 1 with the casing removed, and with the parts shown in different positions. Figs. 9 and 10 are views of parts shown in Figs. 7 and 8 on an enlarged scale.

The machine casing may be of any suitable form and may, as stated, be arranged to slide on guide-ways of a book or sheet of paper, or be held stationary while the paper is fed beneath it. Preferably, it is of light construction, as illustrated, so that the ma-

chine may be readily placed in any desired position upon a book, sales sheet or the like. In the form shown, the casing comprises end plates 10 and side and top walls formed of an inverted U-shaped piece 11 extending between the end plates 10. A pair of intermediate plates 12 are arranged between the end plates 10 and these plates are provided at their upper edges with portions 13, which extend through openings in the top of the casing and between which the totalizer of the machine is arranged. The totalizer, in the form shown, comprises a set of disks 14 mounted on a shaft 15. Each disk is provided with a spur gear 16, which is fixed thereto and which meshes with the gears for controlling the disk. Suitable transfer devices are provided between the totalizer disks 14. In the form shown, transfer pinions 17 are mounted upon a shaft 18 and engage with the disks 14 and the gears 16 thereon, in any suitable manner such that a complete revolution of one of the disks of the totalizer will advance the adjacent disk of higher order one step, or through one-tenth of a revolution. The shafts 15 and 18, whereon the totalizer disks and transfer pinions are mounted, are fixed between projecting parts 13. The totalizer disks and transfer pinions are inclosed within a supplemental casing 19 arranged between the parts 13, and which is provided with an aperture 20 through which the totalizer may be read.

The driving devices for the totalizer are preferably in the form of segmental racks 21 which are pivotally connected at one end to a set of key levers 22. The key levers 22 are pivoted between their ends on a shaft 23 that is journaled in the plates 12 within the casing. The key levers project, as shown, through slots 24 in the upper front portion of the casing and are provided at their ends with finger pieces 25. The key levers are preferably of different lengths, as indicated in Fig. 3, so that the finger pieces 25 thereon may be located far enough apart to be readily manipulated. The segmental racks 21 are provided with spur teeth and each is arranged to engage the teeth of one of a pair of transmission spur gears 26 and 27, which are mounted upon a shaft 28. One of the transmission gears of each pair meshes with the teeth of the corresponding rack 21, while the other transmission gear of the pair meshes with the

driven gear 16 on the corresponding disk of the totalizer. Each rack, as most clearly shown in Figs. 7 and 8, is provided with two sets of teeth 29 and 30. The teeth 29 of the racks are arranged to mesh with the corresponding transmission gears 26, while the teeth 30 are arranged to mesh with a set of pinions 31 that are independently mounted on a shaft 32. The shaft 32 is fixed, as shown, between the plates 12. This gearing between the setting finger keys and racks, and the totalizer disks is particularly designed to enable the machine to effect both additions and subtractions, and 10 will be more fully explained hereinafter. If additions alone were required, a single transmission gear could be employed between each rack and the corresponding totalizer disk or, indeed, the racks could directly engage the totalizer disks.

The racks 21 for setting the totalizer disks are concentric with the shaft 23 whereon the controlling key levers 22 are mounted, so that the racks will properly mesh with 15 the teeth of the pinions 26 and 31 as they are shifted by the key levers. The racks are held into engagement with the pinions of the totalizer by a universal bar 33 which extends through segmental slots 34 formed 20 in the racks. This universal bar also serves to shift the racks out of engagement with the pinions, so that the keys and racks may be restored to normal position, without disturbing the totalizer and, when the keys and 25 racks are so restored, the universal bar is arranged to effect the reengagement of the racks with the totalizer. The universal bar 33 by its engagement with the slots 34 in the racks, properly holds the latter into 30 engagement with the pinions of the totalizer as the racks are shifted by the keys. To move the racks into and out of engagement with the totalizer, the universal bar is radially shiftable to and from the shaft 23. For 35 this purpose the universal bar is fixed at its ends to a pair of radial arms 35, having enlarged inner ends with elongated openings 36 therein, through which the shaft 23 extends. These arms are arranged against 40 the outer faces of the plates 12, as shown, and the ends of the universal bar 33 which are connected to the arms 35 extend through openings 37 in the plates 12, which are of sufficient size to permit the radial shift of 45 the universal bar to throw the racks 21 into and out of engagement with the pinions of the totalizer, and the edges of these openings act to guide the movement of the universal bar in radial direction, but prevent 50 its movement in any other direction. Springs 38 connected to the inner ends of the arms 35 and to pins 39 on the plates 12 tend to pull the universal bar inwardly and the racks 21 out of engagement with the pinions of the totalizer. The racks 21

are, however, normally held in engagement with the totalizer by a pair of cam arms 40 that are fixed to the ends of a shaft 41. This shaft is journaled, as shown, in the plates 12 below the shaft 23. The ends 55 of the shaft extend through the plates and carry the cam arms 40, which engage cam lugs 42 upon the inner ends of the arms 35, and thus serve to normally hold the universal bar 33 in its outward position with 60 the racks 21 meshing with the pinions of the totalizer and with the springs 38 under tension.

As stated, the key levers 22 are journaled upon the shaft 23 and this shaft is preferably employed as a universal restoring member for returning the key levers to initial position. For this purpose, the hub of each key lever is provided with a segmental slot 65 43 and the shaft 23 is journaled in the plates 12 and is provided with a series of pins 44 which extend within the segmental slots 43. These pins normally engage the upper ends of the slots 43, as shown in Fig. 1. When any of the keys are shifted the shaft 23 will 70 be rocked in the direction indicated by the arrow in Fig. 1, by the engagement of the hubs of the key levers with the pins 44 on the shaft. The slots 43 are, however, of such length that the several key levers 22 may be moved independently to variably 75 actuate the racks 21, but by rotating the shaft 23 in reverse direction any of the key levers which have been shifted and the racks 21 connected thereto, will be restored 80 to normal or initial position. To thus rock the universal restoring member or shaft 23 it is provided on one end (as shown in Figs. 2 and 4) with a crank arm 45 which is pivotally connected to one of a pair of toggle 85 links 46. The other toggle link 47 is pivoted to the plate 12 and the joined ends of the toggle links carry an anti-friction roller 48, which is arranged to be engaged by a cam 90 arm 49 on the end of the shaft 41.

When the finger keys 25 have been manipulated to operate the key levers 22 and racks 21 and thus operate the totalizer to add or subtract any sum therefrom, the shaft 23 is rotated in the direction of the arrows 95 shown in Figs. 1 and 4, and the roller 48 on the toggle links 46 and 47 will be moved to a greater or less extent toward the shaft 41. The shaft 41 is then rotated through a complete revolution in the direction of the arrow 100 shown in Fig. 4 and the cam arms 40 will first be disengaged from the lugs 42 on the arms 35, so that the springs 38 may act to shift the universal bar 33 inwardly and 105 disengage the racks 21 from the pinions of the totalizer. The continued movement of the shaft will bring the cam arm 49 into engagement with the roller 48 and thus move the toggle links 46 and 47 to rock the shaft 23 and restore the key levers and racks 21 in 110

115

120

125

130

circumferential direction to normal. The cam arms 40 then reengage the lugs 42 and shift the universal bar 33 back to its normal outward position, thereby placing the racks 21 again in engagement with the totalizer and the springs 38 under tension. The machine is then ready for the next operation.

In order that the different numbers which are added or subtracted may be printed, 10 a set of printing types are connected to and variably operated by the key levers 22. These types are in the form of segments 50 and are each provided with a set of type 56 running from 0 to 9. They are pivotally connected to the lower ends of the key levers 22 and are thus arranged in the lower portion of the machine frame immediately above the paper or paper support, upon which the machine is placed when in use. 20 The pivoted end of each segmental die or printer 50 is provided with an extension 51 and a coiled, cushion spring 52 extending between this extension and a shoulder 53 on the corresponding key lever normally holds 25 the segment into engagement with a projection or stop 54 on the opposite side of the key lever.

It should be noted that the segmental printing types 50 and the segmental racks 30 or drivers for the totalizer are pivotally connected to the opposite ends of the printing key levers and on opposite sides of the axis thereof, and that the printing types and racks are concentric with the pivotal axis of 35 the key levers, so that the racks will properly mesh with the pinions of the totalizer and so that the type on the printing type segments will be brought into proper relation with the surface of the paper or the 40 like, upon which the impression is made.

Each type segment 50 is provided on its upper edge with a series of V-shaped notches 55 which correspond in position with the type 56 on its lower face. These notches 45 are arranged to coöperate with the lower V-shaped or beveled edge 57 of a universal bar 58. This bar extends over the type segments 50 and its ends project through vertical slots 59 in the plates 12. Each end of the 50 universal bar 58 is engaged by the free end of a spring 60, which is fixed at its opposite end to pins 61 on the plate 12. By this means the universal bar is normally upheld 55 within the vertical slots 59.

55 When any number is to be added or subtracted the proper keys of different denominations will be operated to different extents to set up the number. This operation of the key levers will properly advance or retract 60 the totalizer and will variably shift the type segments 50. The latter will be pressed by their springs 52 into engagement with the universal bar 58 and will be held in said position by the engagement of the lower beveled 65 edge 57 of the universal bar with the notches

55 in the upper edges of the type segments. The dies or type segments thus act as detent arms to hold the key levers in set position. After the number to be added or subtracted is set up by the operation of the different denominational key levers, the shaft 41 will, as stated, be rotated through a complete revolution. This, as described, first disengages the racks 21 from the totalizer. The further movement of the shaft will bring 70 the cam arms 40 into engagement with the universal bar 58 and will depress the latter against the tension of the springs 60 to effect the operation of the type segments or dies 50, and thus impress the number which has 80 been set up upon the paper beneath the machine. The further movement of the shaft 41 will move the arms 40 out of engagement with the universal bar 58 and, as previously described, will restore the key levers 22 and 85 racks 21 in circumferential direction, and at the same time will return the type segments or dies to their initial zero position. The universal bar 33 and racks 21 are then restored to normal by the cam arms 40 and 90 the machine is ready for the next operation.

The shaft 41 could be rotated through a single revolution at the end of each operation by hand, if desired. In the preferred construction a spring drum 62 is employed. 95 This drum is mounted upon a stud shaft 63 that projects from one of the plates 12 and is connected by gears 64 and 65 to a winding key 66. It is also connected by gears 67 and 68 to the shaft 41. When the spring 100 mechanism is wound up it tends to rotate the shaft 41 in the direction of the arrows indicated in Figs. 1 and 4. The spring mechanism is, however, normally held against operation by a releasable latch 69, 105 which is pivoted to the inner face of one of the plates 12, and is provided with a toothed upper end which engages a notch in a disk 70 fixed to the shaft 41. The lower end of the latch is connected to a push rod 71 which 110 extends outwardly through the front wall of the machine frame and is provided at its outer end with a push button or key 72. A spring 73 coiled around the push rod 71 between the button 72 and frame, normally 115 holds the latch 68 into engagement with the notch of the disk 69, and the shaft 41 is thus held against movement. A slight push by the operator, however, upon the button 72 will release the latch, so that the spring 120 mechanism will rotate it. After a single revolution of the shaft the latch 68 will reengage the notch of the disk 69 and arrest the movement of the shaft.

The type segments 50, totalizer disks 14 125 and the controlling key levers 22 therefore are, of course, alike in number and represent the different denominations units, tens, hundreds, etc. These parts may vary in number in accordance with the size of the 130

machine. When any number is to be added or subtracted it is first set up by promptly manipulating the finger keys 25 to advance or retract the totalizer through the medium of the driving racks 21 and to shift the type segments or dies 50 from zero into position to print the number. The parts will be held in shifted position by the engagement of the notches 55 on the type segments with the beveled edge 57 of the universal bar 58. Then by pressing the button 72, the operator will release the disk 69 so that the cam shaft 41 will be rotated through a single revolution, and the number which has been set up will be printed and the parts restored, as previously described, to zero position ready for the next operation. To facilitate the setting up of the number by means of the finger keys 25 the front face of the casing adjacent the slots 24 is provided with a series of scales numbered from 0 to 9. As the keys are variably shifted it is difficult to read at a glance the number set up on such a series of scales, and for this reason other indicating means are provided in connection with the finger keys and comprises a set of flat spring strips 74, one of which is connected to each key lever 22 at its outer end and at a point inside and adjacent the wall of the casing. These spring strips extend rearwardly from the upper ends of the key levers and are normally coiled within a cylindrical casing 75, which is set upon the upper portion of the frame immediately behind the normal position of the finger keys. This cylinder 75 is provided, within the main casing, with a slot or opening 76, and with a guiding lip 77 below the slot. Outside of the main casing the cylinder 75 is provided with apertures or a longitudinal slot 78. The numbered spring strips 74 extend through the opening or slot 76 and over the guiding lip 77, and are normally coiled within the cylinder 75, as indicated in Fig. 1. The numbers on the strips are visible through the slot 78 of the cylinder and as the keys are depressed to set up a number the corresponding springs will uncoil and the number set up may be read at a glance through the slot or aperture 78. When the key levers are returned the spring strips will again coil up within the cylindrical casing 75.

To indicate the printing line of the machine the laterally projecting pointers 79 are fixed to the lower edges of the outer end walls 10. The finger keys and the type segments are normally in zero position with the zeros on the type segments opposite the printing line of the machine and immediately below the universal bar 58, which, as described, is depressed to effect the impression of the type segments. In this way it will be unnecessary to set up zeros in operating the machine, but it is desirable that

the zeros to the left of the digit of highest denomination in the number shall not be printed and that all zeros to the right of such digit shall be printed. To effect this, the parts are so arranged that the universal bar 58 will be inoperative upon the type segments when in zero position. In the form shown, the notches 55 in the type segments, which correspond to the zero position thereof, and which are normally located beneath the universal bar, are considerably deeper than the notches 55, so that the limited shift of the universal bar will be insufficient to operate any type segment that is in zero position. To effect the printing of all zeros to the right of the digit of highest denomination in the number, each of the type segments 50, except the one of lowest denomination, is provided on one side and along its upper edge with a laterally projecting segmental rib 80 which engages a segmental shoulder 81 on the side of the next adjacent type segment of lower order. By this means each type segment, when operated by the universal bar 58, will in turn operate the next adjacent segment of lower order when the latter is in zero position, and all zeros to the right of the highest digit of the number will be printed, while those to the left will not.

The type segments or dies 50 are arranged close together, as clearly indicated in Fig. 2, so that the numbers may be compactly written. The operating key levers 22 and racks 21, however, require more room. For this reason the lower ends of the outer key levers are bent inwardly, as clearly shown in Fig. 2.

The type segments or dies could be inked with a roller, if desired, but preferably, an inking ribbon 82 is employed. This ribbon is connected at its opposite ends to a pair of ribbon spools 83 and 84, which are arranged within the spaces between the opposite pairs of plates 10 and 12. The ribbon spool 83 is fixed to a stud shaft 85 that extends through the adjacent end wall 10 and is provided on its outer end with a turning button 86. The ribbon spool 84 is mounted upon a pin or stud shaft 87 which extends through an opening 88 in the adjacent end wall 10 and into a socket 89 in the end of the shaft 23. A Geneva stop gear 90, fixed to the inner face of the ribbon spool 84, is arranged to be engaged by a single toothed Geneva stop pinion 91 upon the end of the cam shaft 41. This shaft, as described, is rotated through one revolution at each operation of the machine, so that the ribbon 82 is gradually wound upon the spool 84. The pin 87 extends loosely through the spool 84 and into the socket 89 of the shaft 23, so that it may be withdrawn out of the socket 89, and the opening 88 in the end wall 10 is elongated slightly, so that the pin may be moved to

70

75

105

110

115

120

125

130

lift the ribbon spool 84 and gear 90 thereon and thus disengage the latter from the pinion 91. Then by turning the shaft 85 through the medium of the turning button 86, the ribbon may be wound back onto the spool 83. For convenience in manipulating the pin 87, it is provided on its outer end with a button 92.

The ribbon passes from the spool 83 downwardly over an inclined guide roller 93 and thence extends transversely through guide openings 94 in the lower edges of the plates 12 to a second inclined guide roller 95, and thence over the winding spool 84. The ribbon is thus fed transversely beneath the type segments or dies 50 or in the direction of the line of printing. The guide rollers 93 and 95 are journaled between ears 96 upon the lower ends of a pair of arms 97. These arms extend upwardly between the end plates 10 and ribbon spools 83 and 84 and pivotally engage the spool shafts or pins 85 and 87. Studs 98 fixed to the lower ends of the arms 97, extend through segmental slots 99 in the end walls 10 so that the arms may be swung to a slight extent to shift the ribbon 82 widthwise or transversely to the printing line so that different portions widthwise of the ribbon may be brought beneath the type 56. In this way different colored portions of the ribbon may be brought beneath the type 56 of the printing dies or segments 50, and the numbers may be printed in different colors, for example, in making out bills and the like it is customary to enter the debits in black or blue ink and the credits in red. To effect this the different widthwise portions of the ribbon which are brought beneath the type by the shift of the arms 97 and guide rollers 93 and 95, are correspondingly colored.

As stated, the machine may be set so that the shift of the finger keys 25 will either add or subtract the number set up by the finger keys. For this purpose, as described, the driver 21 for each of the totalizer disks 14 is provided with two racks or sets of gear teeth 29 and 30. The rack teeth 30 mesh with a set of pinions 31 on a shaft 32, as described. These pinions are loose on the shaft and are held in place thereon and are properly held apart by spacing sleeves 100 mounted on the shaft between the gears or pinions 31, and by collars 101 fixed to the shaft 32 and engaging the outer faces of the end pinions of the set. Each set of gear teeth 29 is arranged to act as a driver to rotate the corresponding totalizer disk in one direction, while each set of gear teeth 30 and the pinion 31 engaged thereby is arranged to act as a driver to rotate the corresponding totalizer disk in the opposite direction. A pair of transmission gears 26 and 27 is interposed between each pair of drivers and the driven gear 16 of the cor-

responding totalizer disk. A yielding connection is provided between each pair of transmission gears 26 and 27 and preferably comprises intermeshing, crowned-toothed ratchets 102 upon the adjacent faces of the two gears 26 and 27 of each pair, so that motion may be transmitted from one gear to the other while each may be rotated independently of the other. The transmission gears are shiftable back and forth in axial direction and each is arranged to alternately engage with the driven gear 16 of the corresponding disk and with one of the oppositely acting drive gears therefor. To effect the axial shift of the pairs of transmission gears, and to hold the ratchet teeth in yielding engagement, these gears are loosely mounted upon the shaft 28 which extends through the plates 12 and 10 and is axially shiftable to a limited extent. Buttons 103 upon the ends of this shaft are employed for convenience in shifting it back and forth, and also act as stops to engage the end walls or plates 10 and limit the movement of the shaft. The shaft 28 is held in one or the other of its two positions by a dog 104 (see Fig. 4), which is pivoted intermediate its ends to one of the side plates 12 and is provided with a beveled end arranged to engage one of a pair of V-shaped, annular grooves 105 formed in the shaft. A spring 106, connected to the opposite end of the dog or latch and to a pin on the plate 12, yieldingly presses the free, beveled end of the dog or latch into engagement with one of the notches 105 in the shaft. The shoulder between the notches 105 is V-shaped or beveled so that, when the shaft is shifted in one or the other direction far enough to move the edge of this shoulder past the dog 105 or latch, the latter will act upon the cam face of the shoulder to complete the shift. The pairs of transmission gears are loosely mounted on the shaft 28 and are held in proper position thereon by a series of loose spacing sleeves 107 that are interposed between the several pairs of gears, and by a collar 108 which is fixed to the shaft in position to engage the end gear 26 of the set. A spring 109 coiled about the shaft 28 presses upon the opposite end gear 27 of the set and holds the ratchet teeth 102 of the entire set of transmission gears in yielding engagement. This spring extends between a collar 110 fixed to the shaft, and a collar 111 which engages the end gear 27.

The transmission gear 26 of each pair is arranged to alternately engage the teeth 29 of the corresponding driving rack, and the teeth of the corresponding gear 16, while the transmission gear 27 is arranged to alternately engage the teeth of the corresponding pinion 31 and the gear 16.

Figs. 7 and 8 show the transmission gears in their two positions for rotating the to- 130

talizer disks 14 in opposite directions and thereby add and subtract. In Fig. 7, the transmission gears 27 engage the drive pinions 31 and the gears 26 engage the driven gears 16 on the totalizer disks. In Fig. 8, the gears 27 engage the driven gears 16, while the gears 26 mesh with the rack teeth 29 of the driving racks. The driving racks 21 are shifted by the finger keys in the direction indicated by the arrows in Figs. 7 and 8. When the parts are in the position shown in Fig. 7, the rack teeth 30 will rotate the pinions 31, the latter will rotate the transmission gears 27 and these gears will drive the totalizer disks through the medium of the ratchet teeth 102, transmission gears 26 and gears 16. When the parts are in the position shown in Fig. 8, the rack teeth 29 will rotate the gears 26 and the latter will drive the totalizer disks in the opposite direction through the medium of the ratchet teeth 102, transmission gears 27 and driven gears 16. In one position of the transmission gears, the numbers set up by the finger keys will be added to the totalizer, while in the other position they will be subtracted therefrom. Preferably, the totalizer disks are so numbered that when the transmission gears are in the position shown in Fig. 8, the totalizer disks will be rotated in forward direction, that is to say, the numbers set up by the finger keys will be added thereto. The transfer devices between the totalizer disks, whereby the one revolution of the units wheel will impart a tenth of a revolution to the tens wheel and so on, will, of course, act independently of the drivers for the individual disks. This independent action of the transfer devices is permitted by the yielding, one-way ratchet connections between the pairs of transmission gears. Whichever one of the two transmission gears 26 and 27 of a pair is in engagement with the gear 16 of the corresponding totalizer disk, it will move independently of the other gear of the pair when its totalizer disk is shifted by the transfer devices, and the ratchet teeth intermediate the pair of transmission gears will slip past each other. As shown, the transmission gears 26 and 27 and the ratchets 102 each have ten teeth, while the gears 16 have twenty teeth, so that the movement of any of the totalizer disks through one step or through one-tenth 55 of a revolution, will require the rotation of the transmission gear in mesh therewith through one-fifth of a revolution or through the space occupied by two teeth. When the parts are in the position shown in Fig. 7, the abrupt faces of the ratchet teeth will be in such position that the gear 26 in mesh with the gears 16 will be properly driven by the gear 27, but the beveled faces of the ratchet teeth will permit the further shift of the 60 totalizer disks 14, gears 16 and transmission

gears 26 by the transfer devices between the disks independently of the transmission gears 27 and the driving pinions 31. In the position of the parts shown in Fig. 8, the abrupt faces of the ratchet teeth 102 will enable the transmission gears 26 to properly rotate the totalizer disks through the medium of the transmission gears 27 and driven gears 16, while the inclined faces of the ratchet teeth will permit the independent movement in the same direction of the totalizer disks, gears 16 and transfer gears 27. When any of the totalizer disks are advanced by the transfer devices, the teeth of two intermeshing ratchets 102 ride over one another and the transmission gears shift slightly along the shaft 28. This yielding shift is permitted by the spring 109, which normally holds the ratchet teeth in engagement. It should be noted that the teeth 29 on the racks 21 form a set of drivers or drive gears for rotating the totalizer disks in one direction, while the pinions 31 form a set of drivers or drive gears for rotating the totalizer disks in the opposite direction. By operating the pinions 31 from the teeth 30 on the racks 21 the same set of finger keys may be employed for rotating the totalizer disks in opposite directions, or for adding and subtracting. It should be further noted that there is a pair of oppositely acting drivers or drive gears for each totalizer disk and a pair of transmission gears between each pair of drive gears and the corresponding totalizer disk. These transmission gears are shiftable, as described, and each is arranged to alternately connect with one of the drive gears and with the corresponding totalizer disk. The one-way, yielding connection between the pair of transmission gears permits the shift of the totalizer disk by the transfer devices independently of the drivers therefor. It should also be noted that the operation of the finger keys, driving racks and printing dies or segments 50 is controlled by three universal members, that is to say, the bar 33 is a universal member for shifting the drivers into and out of engagement with the totalizer, the bar 58 is a universal member for holding the printing dies in set position and for effecting the impression thereof, and the shaft 23 is a universal member for returning the key levers, dies and racks to initial position. These three universal members are preferably controlled, as described, by a single means consisting of the shaft 41, and cam arms thereon, and this controlling means, as stated, is preferably actuated by a spring mechanism that is provided with a releasable latch for normally holding it against operation.

The improved machine may be conveniently employed for printing lines of figures upon sales sheets or books, and for adding

or subtracting the same. In the form shown, the device may be readily shifted about and placed upon the paper wherever it is desired to print lines of numbers. If desired, the machine could be mounted upon guide rails and shifted over a stationary platen upon which the paper or book is held, or the machine itself could be stationary and the paper mounted upon a platen arranged to move beneath the machine. By arranging the machine either for adding or subtracting, it is especially adapted for use in making out bills or statements of account. The debits can be readily added and the credits subtracted, so that the balance due may be readily ascertained. By shifting the ribbon the debits may be printed in black or blue ink and the credits in red ink, as is the common practice. When a computation is completed, the total or result shown by the totalizer will be set up on the finger keys and printed. Before this is done, however, the shaft 28 will be shifted to effect a subtraction, so that in setting up the total or result 25 the totalizer itself will be restored to zero position.

The device is simple, inexpensive, compact and will accurately perform the work as described.

30 It is obvious that numerous changes may be made in the details set forth without departure from the essentials of the invention.

Having described my invention, what I claim as new and desire to secure by Letters 35 Patent, is:—

1. In a calculating machine, the combination of a set of drivers having spur toothed portions, a totalizer having spur pinions for engaging the toothed portions of said drivers, a set of finger keys for variably shifting said drivers, a universal member for throwing said drivers and said spur pinions into and out of engagement, a second universal member for restoring said drivers and 45 said finger keys, and means independent of said key mechanism for successively operating said universal members, substantially as described.

2. In a calculating machine, the combination 50 with a totalizer having a set of spur pinions, a set of toothed driving racks normally meshing with said pinions, finger key mechanism directly connected to said racks to shift the same in opposite directions and set said totalizer, and means independent of said key mechanism for disengaging said racks and said pinions, for restoring said racks and key mechanism to initial position and for reengaging said racks and pinions, 55 substantially as described.

3. In a calculating machine, the combination 60 with a totalizer having a set of spur pinions, of a set of spur toothed driving racks normally meshing with said pinions, finger key mechanism for variably shifting

said racks to advance said totalizer, a universal bar for shifting said racks into and out of engagement with said spur pinions, and means independent of said key mechanism for operating said universal bar and 70 for restoring said racks and key mechanism while said racks are disengaged from said pinions, substantially as described.

4. In a calculating machine, the combination 75 with a totalizer having a set of spur pinions, of a set of spur toothed driving racks normally meshing with said pinions, a set of finger keys, one for each of said racks, for variably shifting the same to advance said totalizer, a universal member 80 for shifting said racks into and out of engagement with said spur pinions, a universal member for restoring said racks and said keys, and means independent of said key mechanism for successively operating 85 said universal members to disengage said racks, restore said racks and keys while said racks are disengaged from said pinions and reengaging said racks with said pinions, substantially as described. 90

5. In a calculating machine, the combination 95 with a totalizer comprising a number of counter wheels each having a spur-toothed pinion, a series of pivoted levers provided with finger keys, a series of segmental racks connected to said key levers to shift in opposite directions therewith normally geared to said pinions, and means independent of said key levers for engaging and disengaging said racks and totalizer 100 and for restoring said racks and key levers to initial position while disconnected from said totalizer, substantially as described.

6. In a calculating machine, the combination 105 of a series of pivoted key-levers, a series of segmental racks pivoted to said key-levers, a totalizer having a series of counter wheels and a corresponding series of pinions meshing respectively with said racks, means controlled independently of said key 110 levers for shifting said racks into and out of engagement with said pinions and means for restoring said racks and key-levers to initial position.

7. In a calculating machine, the combination 115 of a series of key-levers pivoted on a common axis, a series of segmental racks concentric with the axis of said key-levers and pivotally connected thereto, a totalizer having a series of pinions meshing 120 with said racks, a universal bar engaging said racks for shifting the same into and out of engagement with said pinions, and means for restoring said racks and levers to initial position. 125

8. In a calculating machine, the combination 130 with a casing, of a shaft mounted in said casing, a series of key-levers journaled on said shaft, a series of segmental racks pivoted to said key-levers and variably op-

erated thereby, a totalizer in said casing arranged to be differentially operated by said racks, a universal bar connected to said series of racks, and means for operating said 5 universal bar to throw said racks into and out of engagement with said totalizer and for restoring said racks and key-levers to initial position.

9. In a calculating machine, the combination with a casing, of a shaft mounted in said casing, a series of key-levers journaled on said shaft and projecting through slots in said casing, a series of segmental racks pivoted to said key-levers and variably operated thereby, a totalizer having a series of pinions meshing with said racks, a radially shiftable universal bar mounted on said shaft and engaging a series of segmental slots formed in said racks, and 20 means for shifting said universal bar to throw said racks into and out of engagement with said pinions and means for restoring said key-levers and said racks while the latter are disengaged from said pinions.

25 10. In a calculating machine, the combination of a series of pivoted key-levers, a series of racks pivoted to said key-levers, a totalizer having a series of pinions meshing with said racks, a universal bar engaging slots in said racks for guiding and holding the same in mesh with said pinions, means for shifting said universal bar to throw said racks into and out of engagement with said pinions, and means for restoring said 35 key-levers and said racks when the latter are out of engagement with said pinions.

11. In a calculating machine, the combination of a series of finger pieces, a series of racks connected to and variably operated 40 by said finger-keys, a totalizer having a series of pinions meshing with said racks, a universal bar engaging slots in said racks, said universal bar being shiftable to throw said racks into and out of engagement with 45 said pinions, a spring for shifting said universal bar in one direction and a cam for shifting said universal bar in the other direction.

12. In a calculating machine, the combination with a set of finger-keys, of a set of 50 racks connected to and variably shifted by said finger-keys, a totalizer operated by said racks, a universal member for shifting said racks into and out of engagement with said 55 totalizer, a universal member for restoring said racks, and means for successively operating said universal members.

13. In a calculating machine, the combination with a series of finger-keys, of a series 60 of racks connected to and variably operated by said finger-keys, a totalizer having a series of pinions for engaging said racks, a universal member for shifting said racks into and out of engagement with said pin-

ions, spring-actuating mechanism controlling the operation of said universal member, a releasable latch for throwing said spring mechanism into operation, and means operated by said spring mechanism for restoring said racks and finger-keys when said racks 70 are disengaged from said pinions.

14. In a calculating machine, the combination with a casing, of a shaft journaled in said casing, a series of key-levers journaled on said shaft and having a lost-motion, pin-and-slot connection therewith, a series of segment racks pivoted to said key-levers, a totalizer having a series of pinions meshing with said racks, a universal member for shifting said racks into and out of engagement with said pinions, mechanism controlling the movement of said universal member, and means controlled by said mechanism for rocking said shaft and restoring said racks and key-levers when said racks 85 are disengaged from said pinions.

15. In a calculating machine, the combination of a set of finger-keys, a set of drivers connected to and variably operated by said keys, a totalizer differentially operated by 90 said drivers, spring-actuated mechanism for shifting said drivers and said totalizer into and out of engagement and for restoring said setting devices and said finger-keys and a releasable trip controlling the operation of 95 said spring mechanism.

16. In a calculating machine, the combination with a casing, of a shaft in said casing, a series of key-levers journaled on said shaft and having a lost-motion, pin-and-slot connection therewith, a series of segment racks pivoted to said key-levers, a totalizer having a series of pinions meshing with said racks, a universal member engaging said racks and shiftable to move said racks into 100 and out of engagement with said pinions, a spring-actuated cam shaft controlling the shift of said universal member, means actuated by said cam shaft for rocking said first mentioned shaft to restore said racks 110 and key-levers to initial position, and a releasable latch for holding said spring actuated cam shaft against operation.

17. In a calculating machine, the combination with a casing, of a shaft journaled 115 in said casing, a series of key-levers journaled on said shaft and having lost-motion connections therewith, a series of drivers connected to said key-levers and variably shifted thereby, a totalizer controlled by 120 said setting devices, and means for rocking said shaft to restore said key-levers and said drivers.

18. In a calculating machine, the combination with a totalizer, of a series of drivers variably shifted from initial position 125 for operating said totalizer, a spring-driven universal member for restoring all of said

drivers to initial position and a releasable catch for holding said member against operation.

19. In a calculating machine, the combination of a totalizer, a series of pivoted finger keys, a series of drivers for said totalizer connected to and variably operated by said finger keys, a segmental printing die carried by each of said finger keys disposed substantially concentric with the pivot thereof and a universal member for restoring said finger keys to normal position.

20. In a calculating machine, the combination with a casing, a series of key-levers journaled in said casing and projecting therefrom, a series of racks connected to and variably operated by said key-levers, a totalizer having a series of pinions meshing with said racks, a universal bar for shifting said racks into and out of engagement with said pinions, a universal member for restoring said key-levers and said racks when the latter are out of engagement with said pinions, and means controlling the successive 25 operation of said universal members.

21. In a calculating machine, the combination with a casing, of a series of key-levers journaled in said casing, a series of racks connected to and variably operated by said key-levers, a totalizer having a series of pinions meshing with said racks, a universal member for throwing said racks into and out of engagement with said pinions, a universal member for restoring said key-levers and said racks when the latter are out of engagement with said pinions, a spring-actuated mechanism controlling the successive operation of said universal members, and a releasable latch for holding said 40 spring mechanism against operation.

22. In a calculating machine, the combination with a casing, of a shaft journaled in said casing, a series of key-levers journaled on said shaft and having lost-motion 45 connections therewith, of a series of segmental racks pivoted to and variably operated by said key-levers, a radially shiftable universal bar mounted on said shaft and connected to said racks to throw the same 50 into and out of engagement with said pinions, and mechanism for successively shifting said universal bar and said shaft to restore said racks and said key-levers to initial position.

23. In a calculating machine, the combination with a casing, of a shaft journaled in said casing, a series of key-levers journaled on said shaft, pins on said shaft engaging segmental notches in said key-levers, 10 a series of segmental racks pivoted to and variably operated by said key-levers, a universal bar engaging slots in said key-levers, a series of pinions meshing with said racks, a totalizer controlled by said pinions, said 15 universal bar being radially shiftable on

said shaft to throw said racks into and out of engagement with said pinions, a spring-actuated cam shaft, means on said cam shaft controlling the operation of said universal bar, means on said cam shaft for rocking 70 said first mentioned shaft to restore said key-levers and said racks when the latter are out of engagement with said pinions, and a releasable latch for holding said spring actuated cam shaft against operation. 75

24. In a calculating machine, the combination with a set of totalizer disks and transfer devices between said disks, of oppositely-acting driving means for each of said disks, 80 and two transmission gears having a yielding, one-way connection interposed between said driving means and the disk operated thereby, said transmission gears being shiftable and each arranged to alternately connect with said disks and said driving means. 85

25. In a calculating machine, the combination with a set of totalizer disks and transfer devices between said disks, of a set of oppositely-acting driving mechanisms, one for 90 each totalizer disk, and a set of transmission gears between said driving mechanisms and said disks, said transmission gears being arranged in pairs, one pair between each disk and the driving mechanism therefor 95 and the gears of each pair having a one-way yielding connection, said transmission gears being shiftable and each arranged to alternately connect with the corresponding disk and the driving mechanism therefor, and a 100 set of finger-keys controlling the operation of said driving mechanisms.

26. In a calculating machine, the combination with a set of totalizer disks and transfer devices between said disks, of a pair of 105 oppositely-acting drivers for each of said disks, two transmission gears having a yielding, one-way connection interposed between each pair of drivers and the disk operated thereby, said transmission gears being shiftable and each arranged to alternately connect with said disk and with one of the 110 drivers therefor.

27. In a calculating machine, the combination with a set of totalizer disks and transfer devices between said disks, of a number 115 of pairs of oppositely-acting drivers, one pair for each of said disks, a number of pairs of transmission gears, one pair being interposed between each pair of drivers and the corresponding disk, the transmission gears of each pair having a yielding, one-way connection, said transmission gears being shiftable and each arranged to alternately connect with the corresponding disk 120 and with one of the drivers of the corresponding pair, and a set of controlling finger-keys, one for each pair of oppositely acting drivers. 125

28. In a calculating machine, the combi- 130

nation with a set of totalizer disks and transfer devices between said disks, of a number of pairs of oppositely acting drivers, one pair for each disk, two transmission gears interposed between each pair of drivers and the corresponding disk, a yielding, one-way connection between each pair of transmission gears, and means for shifting said transmission gears to alternately 10 throw each one of said gears into and out of connection with the corresponding disk and one of the drivers therefor.

29. In a calculating machine, the combination with a set of totalizer disks and transfer devices between said disks, of oppositely acting driving means for each of said disks, and a pair of transmission gears having a yielding ratchet connection interposed between said driving means and the disk operated thereby, said transmission gears being shiftable and each arranged to alternately connect with said disk and with the driving means therefor.

30. In a calculating machine, the combination with a series of totalizer disks and transfer devices between said disks, of a pair of oppositely acting drivers for each of said disks, a pair of transmission gears having a yielding ratchet connection interposed between each pair of drivers and the disk operated thereby, said transmission gears being shiftable and each arranged to alternately connect with the corresponding disk and with one of the drivers therefor, and a set of controlling finger-keys, one for each pair of drivers.

31. In a calculating machine, the combination with a set of totalizer disks and transfer devices between said disks, of a pair of oppositely acting drive gears for each of said disks, and a driven gear connected to each disk, a pair of transmission gears having a yielding, ratchet connection interposed between each pair of drive gears and each driven gear, said transmission gears being shiftable and each arranged to alternately engage said driven gear and one of said driving gears.

32. In a calculating machine, the combination with a set of totalizer disks and with transfer devices between said disks, of a pair of oppositely acting drive gears for each of said totalizer disks, a driven gear connected to each of said disks, a pair of transmission gears having a yielding, ratchet connection interposed between each pair of drive gears and the gear driven thereby, said transmission gears being shiftable and each arranged to alternately engage with the corresponding driven gear and with one of the drive gears therefor, and a set of controlling finger-keys, one for each pair of drive gears.

33. In a calculating machine, the combination with a set of totalizer disks and trans-

fer devices between said disks, of a pair of intermeshing, oppositely acting drive gears for each of said disks, a driven gear connected to each of said totalizer disks, a pair of transmission gears interposed between each pair of drive gears and each driven gear, each pair of transmission gears having a yielding, ratchet connection, said transmission gears being shiftable and each arranged to alternately engage the corresponding driven gear and one of the drive gears therefor, and a set of finger-keys, each connected to one of the drivers of each pair and arranged to variably operate the same.

34. In a calculating machine, the combination with a set of totalizer disks and transfer devices between said disks, of a single shaft whereon said disks are mounted, oppositely acting driving mechanism for each of said disks, a pair of transmission gears having a one-way acting, yielding connection interposed between each driving mechanism and the corresponding disk, and a longitudinally shiftable shaft whereon said transmission gears are yieldingly mounted, and each of said gears being arranged to alternately connect with the corresponding disk and the driving mechanism therefor.

35. In a calculating machine, the combination with a single axis totalizer having a series of disks and transmission devices between the disks, of a pair of intermeshing, oppositely acting driving gears for each of said disks, a driven gear connected to each of said disks, a pair of transmission gears interposed between each pair of drive gears and the corresponding driven gear, a longitudinal shaft whereon said transmission gears are yieldingly mounted, each of said transmission gears being arranged to alternately engage the corresponding driven gear and one of the drive gears therefor, and a set of finger-keys controlling the operation of said drive gears.

36. In a calculating machine, the combination with a set of totalizer disks and transfer devices between the disks, of a set of key-levers, a series of driving racks connected to and variably operated by each of said key-levers, a set of oppositely acting driving pinions meshing with said racks, driven gears connected to said totalizer disks, and a pair of transmission gears interposed between each driven gear and the oppositely acting driven pinion and drive rack therefor, each pair of transmission gears having a yielding, one-way ratchet connection between them, said transmission gears being shiftable and one gear of each pair being arranged to alternately engage the corresponding driven gear and the drive rack therefor and the other to alternately engage said driven gear and the oppositely acting drive pinion therefor.

37. In a calculating machine, the combina-

- tion with a set of totalizer disks and transfer devices between the disks, of a set of key-levers, a set of racks connected to and variably operated by said key-levers, a set of oppositely acting drive pinions driven from said racks, a driven gear connected to each of said totalizer disks, a pair of transmission gears interposed between the driven gear and the oppositely acting pinion and drive rack therefor, each pair of transmission gears having a yielding, one-way ratchet connection, said transmission gears being shiftable and one gear of each pair being arranged to alternately engage the corresponding driven gear and the drive rack therefor and the other to alternately engage said driven gear and the oppositely acting drive pinion therefor, and means for shifting said racks into and out of engagement with said drive pinions and said transmission gears and for restoring said key-levers and said racks when the latter are in disengaged position.
38. In a calculating machine, the combination with a casing, of a series of key-levers arranged within said casing, and projecting therefrom, a series of segment racks connected to and variably operated by said key-levers, a set of oppositely acting drive pinions driven from said racks, a set of totalizer disks, transfer devices between said disks, a pair of transmission gears interposed between each rack and drive pinion and the corresponding totalizer disk, each pair of transmission gears having a yielding, one-way ratchet connection, a longitudinally shiftable shaft whereon said transmission gears are mounted, said transmission gears being arranged to alternately engage the corresponding totalizer disk and one of the drive members therefor, and means for shifting said racks into and out of mesh with said drive pinions and said transmission gears and for restoring said key-levers and said racks when the latter are in disengaged position.
39. In a calculating machine, the combination with a casing, of a totalizer in said casing comprising a set of disks and transfer devices between said disks, of a set of finger-keys, a pair of oppositely acting drive gears connected to and variably operated by each of said finger-keys, a driven gear connected to each of said totalizer disks, a pair of transmission gears having a yielding, ratchet connection interposed between each pair of drive gears and the corresponding driven gear, said transmission gears being shiftable and each arranged to alternately engage the corresponding driven gear and one of the drive gears therefor, and means for disengaging said drive gears from said transmission gears and for restoring the drive gears to initial position.
40. In a calculating machine, the combination with a totalizer, and a series of printing dies each having a series of type, of a series of finger keys for controlling said totalizer and setting said printing dies, a shaft having means for operating said dies, spring driven gearing for rotating said shaft and a releasable latch normally holding said shaft against operation, substantially as described.
41. The combination with a series of printing dies, of a set of finger-keys for setting said dies, a universal member for operating said dies, a spring actuating cam shaft for operating said member and a releasable pawl for holding said shaft against operation.
42. The combination with a suitable casing arranged to be moved over the paper to be printed upon, of a set of printing dies mounted at the lower portion of said casing, a set of finger-keys for variably shifting said dies to set position, means for holding said dies in set position, a universal bar for actuating said dies, and means for operating said universal bar and for restoring said dies and keys to initial position.
43. The combination with a suitable frame of a series of setting key-levers journaled in said frame, a set of segmental printing dies pivoted to said key-levers and arranged concentric with the pivots thereof, means for holding said dies in set position, and means for effecting the operation of said dies and for restoring the same to initial position.
44. The combination with a suitable casing, of a shaft in said casing, a series of key-levers journaled on said shaft, a series of segmental printing dies pivotally connected to said key-levers and arranged concentric with said shaft, and means for holding said printing dies in set position and for effecting the operation thereof.
45. The combination with a suitable casing arranged to be moved over the paper to be printed upon, of a series of setting key-levers arranged within said casing, a series of spring-held segmental dies pivoted to said key-levers and arranged in the lower portion of said casing, a universal bar for effecting the operation of said dies and for holding the same in set position, spring mechanism for effecting the operation of said universal bar and for restoring said dies and key-levers to initial position, and a releasable latch for holding said spring mechanism against operation.
46. The combination with the machine frame, of a set of key-levers pivoted on said frame, a set of printing dies connected to said key-levers and variably shifted in one direction thereby to set position, and means mounted on said frame for moving said dies in another direction independently of said key-levers to effect the impression thereof.
47. The combination with the machine frame, of a set of key-levers pivoted on a

- common axis in said frame, a set of printing dies arranged in the lower portion of said frame and connected to said key-levers to be variably shifted thereby in one direction, 5 means for holding said dies in set position, actuating means mounted on said frame for shifting said dies in another direction independently of said key-levers to effect the impression thereof and means for restoring 10 said dies and key-levers to initial position.
48. The combination with the machine frame, of a set of finger-keys mounted in said frame, a set of printing dies variably shifted to set position by said keys, means 15 for holding said dies in set position, actuating mechanism for effecting the impression of said dies, means for restoring said dies to initial position, a spring for operating said actuating mechanism and said restoring 20 means, and a releasable latch for holding said spring against operation.
49. The combination with the machine frame, of a set of finger-keys mounted thereon, a set of printing dies variably shifted to 25 set position by said keys, a universal bar for shifting said dies independently of said keys to effect the impression thereof and means for operating said universal bar and for restoring said dies to initial position.
50. The combination with the machine frame, of a set of key-levers pivotally mounted in the machine frame, a set of segmental printing dies pivotally connected to said key-levers and arranged concentric with the 30 pivots thereof, said printing dies being variably shiftable by said key-levers to set position and means for shifting said dies independently of said key-levers to effect the impression thereof.
51. The combination with the machine frame, of a set of key-levers pivotally mounted on the machine, a common axis in the machine frame, a set of segmental dies pivoted to said key-levers and arranged concentric 35 with the axis thereof, said key-levers being arranged to variably shift said dies to set position, a universal bar common to all of said dies, means for operating said universal bar to effect the impression of said dies and 40 means for restoring said dies and key-levers to initial position.
52. The combination with the machine frame, of a set of key-levers pivotally mounted upon a common axis in the machine frame, a set of segmental printing dies pivoted to said key-levers and arranged concentric with the axis thereof, a universal bar extending across said segmental dies and arranged to hold the same in the position to 45 which they are set by said key-levers and means for operating said universal bar to effect the impression of said dies and for restoring said dies and key-levers to initial position.
53. The combination with the machine frame, of a set of key-levers pivotally mounted upon a common axis in the machine frame, a set of segmental printing dies pivoted to said key-levers and arranged concentric with the axis thereof, a universal bar extending across said segmental dies and arranged to hold the same in the position to which they are set by said key-levers and means for operating said universal bar to effect the impression of said dies and for restoring said dies and key-levers to initial position.
54. The combination with the machine frame, of a shaft journaled therein, a series of key-levers pivotally mounted on said shaft, a set of segmental printing dies pivoted to said key-levers and arranged concentric with said shaft, a universal bar common to said printing dies, means for operating said universal bar to effect the impression of said dies and means for rocking said shaft to restore said key-levers and said printing dies.
55. The combination with the machine frame, of a set of key-levers pivotally mounted in the machine frame, a set of printing dies connected to said key-levers and variably shifted thereby to set position, a universal bar arranged to engage said segmental dies and hold the same in set position, and means for operating said universal bar to effect the impression of said dies.
56. The combination with the machine frame, of a set of key-levers pivotally mounted in the frame, a set of printing dies connected to said key-levers, a universal bar arranged to engage and hold said dies in the position to which they are set by said key-levers, and an actuator shaft having cams thereon for operating said universal bar to effect the impression of said dies.
57. The combination with the machine frame, of a shaft journaled in said frame, a set of key-levers pivotally mounted on said shaft, a set of printing dies connected to said key-levers and arranged to be variably shifted thereby to set position, a universal bar extending across said dies and arranged to engage the same and hold them in set position, a cam shaft, cams on said shaft for operating said universal bar to effect the impression of said dies, and means operated by said cam shaft for rocking said first mentioned shaft to restore said key-levers and said dies.
58. The combination with the machine frame, of a shaft journaled in said frame, a set of key-levers pivoted on said shaft and having a lost-motion, pin-and-slot connection therewith, a set of printing dies connected to said key-levers, and arranged to be variably shifted thereby to set position, means for holding said dies in set position and for shifting the same to effect the impression thereof, and actuating de-

vices for said means arranged to operate said shaft to restore said key-levers and said dies to initial position.

59. The combination with the machine frame, of a shaft journaled therein, a set of key-levers pivotally mounted intermediate their ends upon said shaft and having a lost-motion, pin-and-slot connection therewith, a set of printing dies connected to 10 said key-levers, a universal bar common to said printing dies, said dies being spring-held into engagement with said universal bar and having a series of notches arranged 15 to engage the edge thereof and be held thereby in set position, actuator mechanism for shifting said universal bar to effect the impression of said dies, and means operated by said mechanism for shifting said shaft to restore said dies and key-levers to initial 20 position.

60. The combination with the machine frame, of a shaft journaled therein, a set of key-levers pivotally mounted intermediate their ends upon said shaft, a set of segmental printing dies arranged in the lower portion of said frame and pivoted to said key-levers to be variably shifted thereby to set position, a universal bar extending above said dies, said dies being spring-held into 25 engagement with said universal bar and having a series of notches arranged to engage the edge thereof, whereby said dies are held in set position, an actuating cam shaft, cams on said shaft for shifting said 30 universal bar to effect the impression of said dies, a cam on said shaft for rocking the shaft whereon the key-levers are mounted to restore the key-levers and segmental dies to initial position, an actuating spring 35 for said cam shaft, and a releasable latch 40 for holding said actuating spring against operation.

61. In a numeral printing machine, the combination with a set of finger-keys and 45 a totalizer controlled thereby, of a set of numeral dies variably shifted to set position by said finger-keys, a universal bar common to said dies and means for operating said universal bar for effecting the impression of said dies, said universal bar being inoperative upon said dies when the latter are in zero position, and each of said 50 dies overlapping the next adjacent die of lower order to effect the operation thereof 55 when in zero position.

62. In a numeral printing machine, the combination with a set of numeral dies, means for variably shifting said dies and a totalizer controlled by said shifting means, 60 of means for effecting the impression of said dies, said means being inoperative in the zero position of the dies and each of said dies being arranged to operate the next adjacent die of lower order when in zero 65 position.

63. In a numeral printing machine, the combination with the machine frame, of a set of key-levers pivotally mounted in the frame, a totalizer controlled thereby, a set of numeral dies connected to said key-levers and variably shifted thereby to set position, and means for shifting said dies to effect the impression thereof, said means being inoperative on said dies when the latter are in zero position, and each of said dies having a projection overlapping the next adjacent die of lower order to operate the same in zero position. 70

64. The combination with the machine frame, of a set of key-levers pivotally mounted in the frame, a totalizer controlled by said key levers, a set of segmental numeral dies pivoted to said key-levers and variably shifted thereby to set position, and a universal bar for operating said dies to 80 effect the impression thereof, said universal bar being inoperative upon the dies when the latter are in zero position, and each of said dies having a projection overlapping the next adjacent die of lower order. 85

65. In a numeral printing and calculating machine, the combination of a set of finger-keys, of a set of printing dies and a set of drivers variably operated by said key-levers, means for shifting said dies independent of 85 said finger-keys to effect the impression thereof, a totalizer operated by said drivers, and means for shifting said drivers into and out of engagement with said totalizer.

66. In a numeral printing and calculating machine, the combination with a set of key-levers, of a set of numeral dies and a set of drivers connected to and variably shifted by said key-levers, a totalizer operated by said drivers, means for effecting the impression 100 of said dies, and means for shifting said drivers into and out of engagement with said totalizer and for restoring said key-levers and the parts operated thereby to 105 initial position. 110

67. In a numeral printing and calculating machine, the combination with a set of finger-keys, of a set of numeral dies and a set of drivers variably operated by said finger-keys, a totalizer actuated by said drivers, 115 means for throwing said totalizer and said drivers into and out of engagement, means for making the impression of said dies, and means for restoring said dies and drivers to initial position. 120

68. In a numeral printing and calculating machine, the combination with the machine frame, of a set of key-levers pivotally mounted in the machine frame, a set of numeral dies and a set of drivers connected to 125 and variably shifted to set position by said key-levers, means for holding said parts in set position, and mechanism for effecting the impression of said dies for disengaging said drivers and said totalizer and for restoring 130

said drivers, said dies and said key-levers to initial position.

5 69. In a numeral printing and calculating machine, the combination with a set of finger-keys, of a set of numeral dies and a set of drivers connected to and variably operated by said finger-keys, a totalizer differentially operated by said drivers, and mechanism for effecting the impression of 10 said dies and for restoring said dies and drivers to initial position, a spring for actuating said mechanism, and a releasable latch for holding said spring against operation.

15 70. In a numeral printing and calculating machine, the combination with a set of finger-keys, of a set of numeral dies and a set of drivers connected to and variably operated by said finger-keys, a totalizer differentially actuated by said drivers, a universal bar coöoperating with said dies and arranged to hold the same and said drivers in set position, and mechanism for operating said universal bar to effect the impression of 25 said dies.

30 71. In a numeral printing and calculating machine, the combination with a set of finger-keys, of a set of numeral dies and a set of driving racks connected to and variably shifted by said finger-keys, a totalizer differentially operated by said driving racks, means for shifting said racks into and out of engagement with said totalizer, means for effecting the impression of said printing 35 dies, and means for restoring said dies and racks to initial position.

40 72. In a numeral printing and calculating machine, the combination with a set of finger-keys, of a set of numeral dies and a set of driving racks connected to and variably operated by said finger-keys, a totalizer variably operated by said driving racks, means for holding said numeral dies in set position and for effecting the impression thereof, 45 means for throwing said racks and totalizer into and out of engagement, and means for restoring said dies and racks to initial position.

50 73. In a numeral printing and calculating machine, the combination with the machine frame, of a set of key-levers pivotally mounted in the machine frame, of a set of numeral dies and a set of driving racks pivoted to said key-levers on opposite sides of 55 the axis thereof, a totalizer driven by said racks, and mechanism for effecting the impression of said dies and for restoring said key-levers and parts operated thereby to initial position.

60 74. In a numeral printing and calculating machine, the combination with a set of pivotally mounted key-levers, of a set of segmental numeral dies and a set of segmental driving racks pivoted to said key-levers on 65 opposite sides of the pivots thereof and ar-

ranged to be variably operated thereby, a totalizer operated by said racks, and means for effecting the impression of said dies.

75. In a numeral printing and calculating machine, the combination with a set of key-levers pivotally mounted upon a common axis, of a set of numeral dies and a set of driving racks pivoted to said key-levers on opposite sides of the axis thereof, a totalizer actuated by said racks and means for effecting the impression of said dies and for restoring said key-levers, dies and racks to initial position. 79

80 76. In a numeral printing and calculating machine, the combination with the machine frame, of a set of key-levers pivotally mounted in the machine frame upon a common axle, a set of numeral dies and a set of driving racks pivotally connected to said key-levers on opposite sides of the axis thereof, a totalizer operated by said driving racks, and mechanism for effecting the impression of said dies, for shifting said racks into and out of engagement with said totalizer and for restoring said key-levers, racks 90 and dies to initial position.

95 77. In a numeral printing and calculating machine, the combination with the machine frame, of a set of key-levers pivotally mounted in the machine frame upon a common axis, a set of numeral dies and a set of driving racks pivotally connected to said key-levers on opposite sides of the axis thereof and arranged to be variably operated thereby, a totalizer operated by said 100 racks, means for shifting said racks into and out of engagement with said totalizer, means for holding said numeral dies in set position and for effecting the impression thereof and means for restoring said key-levers, dies and racks to initial position. 105

110 78. In a numeral printing and calculating machine, the combination with a set of key-levers pivotally mounted in the machine frame upon a common axis, a set of segmental numeral dies and a set of segmental driving racks pivoted to said key-levers on opposite sides of the axis thereof, a totalizer operated by said driving racks, spring actuated mechanism, means controlled by said 115 mechanism for holding said dies in set position and for effecting the impression thereof, means controlled by said mechanism for throwing said racks into and out of engagement with said totalizer, means controlled 120 by said mechanism for restoring said key-levers, dies and racks to initial position, and a releasable latch for holding said mechanism against operation.

125 79. In a numeral printing and calculating machine, the combination with a set of finger-keys, of a set of numeral dies and a set of drivers connected to and variably operated by said finger-keys, a universal member for effecting the impression of said dies, a 130

totalizer driven by said drivers, a universal member for throwing said drivers into and out of engagement with said totalizer, and means controlling the operation of said universal members.

80. In a numeral printing and calculating machine, the combination with a set of finger-keys, of a set of numeral dies and a set of drivers connected to and variably shifted by said finger-keys, a totalizer operated by said drivers, a universal member for shifting said drivers into and out of engagement with said totalizer, a universal member for effecting the impression of said printing dies and means controlling the operation of said universal members and for restoring said dies and drivers to initial position.

81. In a numeral printing and calculating machine, the combination with a set of finger-keys, of a set of numeral dies and a set of drivers connected to and variably shifted by said finger-keys, a totalizer operated by said drivers, a universal member for throwing said members into and out of engagement with said totalizer, a universal member for holding said printing dies in set position and for effecting the impression thereof, and means controlling the operation of said universal member and for restoring said dies and drivers to initial position.

82. In a numeral printing and calculating machine, the combination with a set of finger-keys, of a set of driving racks and a set of numeral dies connected to and variably operated by said finger-keys, a totalizer actuated by said driving racks, a universal member for shifting said racks into and out of engagement with said totalizer, a universal member for effecting the impression of said dies, spring-actuated mechanism for controlling the operation of said universal members and for restoring said dies and racks to initial position, and a releasable latch for holding said spring mechanism against operation.

83. In a numeral printing and calculating machine, the combination with a set of key-levers pivotally mounted upon a common axis, of a set of segmental numeral dies and a set of segmental driving racks pivoted to said key-levers on opposite sides of the axis thereof, a totalizer operated by said racks, a universal bar for shifting said racks into and out of engagement with said totalizer, a universal bar for effecting the impression of said dies, and means for operating said universal bars and for restoring said key-levers, racks and dies to initial position.

84. In a numeral printing and calculating machine, the combination with the machine frame, of a set of key-levers mounted in the frame upon a common axis, a set of segmental numeral dies and a set of segmental driving racks pivoted to said key-levers on opposite sides of the axis thereof, a totalizer ac-

tuated by said racks, a universal bar engaging said racks for shifting the same into and out of engagement with said totalizer, a universal bar for holding said printing dies in set position and for effecting the impression thereof, and mechanism for effecting the operation of said universal bars and for restoring said key-levers, dies and racks to initial position.

85. In a numeral printing and calculating machine, the combination with a set of finger-keys, of a set of numeral dies and a set of drivers connected to and variably operated by said finger-keys, a totalizer actuated by said drivers, a universal member for throwing said drivers into and out of engagement with said totalizer, a universal member for effecting the impression of said dies, a universal member for restoring said dies and racks to initial position, and mechanism for controlling the successive operation of said universal members.

86. In a numeral printing and calculating machine, the combination with a set of key-levers, of a set of numeral dies and a set of driving racks connected to and variably operated by said key-levers, a totalizer actuated by said driving racks, a universal member for shifting said racks into and out of engagement with said totalizer, a universal member for effecting the impression of said dies, a universal member co-operating with said key-levers for restoring the same and said dies and racks to initial position, and means controlling the successive operation of said universal members.

87. In a numeral printing and calculating machine, the combination with the machine frame, of a shaft journaled in the machine frame, a set of key-levers pivotally mounted on said shaft and having a lost-motion, pin-and-slot connection therewith, a set of segmental numeral dies and a set of segmental driving racks pivoted to said key-levers on opposite sides thereof, a totalizer differentially operated by said racks, a universal bar engaging said racks for shifting the same into and out of engagement with said totalizer, a universal bar engaging said numeral dies for holding the same in set position and for effecting the impression thereof, and mechanism for successively operating said universal bars and for rocking said shaft to restore said key-levers, dies and racks to initial position.

88. In a numeral printing and calculating machine, the combination with the machine frame, of a shaft journaled in the frame, a set of key-levers pivotally mounted on said shaft and having a lost-motion, pin-and-slot connection therewith, a set of segmental numeral dies and a set of segmental driving racks pivoted to said key-levers on opposite sides of the center thereof, a totalizer differentially operated by said driving racks, a

universal bar engaging said racks for shifting the same into and out of engagement with said totalizer, a universal bar engaging said printing dies for holding the same in set position and for effecting the impression thereof, and cam mechanism for controlling the successive operation of said universal bars and for rocking said shaft to restore said key-levers, dies and racks to initial position.

89. In a numeral printing and calculating machine, the combination with the machine frame, of a shaft journaled in the frame, a set of key-levers pivotally mounted on said shaft, and having a lost-motion, pin-and-slot connection therewith, a set of numeral dies and a set of driving racks pivotally connected to said key-levers on opposite sides of the axis thereof, a totalizer operated by said driving racks, a universal bar engaging said racks for throwing the same into and out of engagement with said totalizer, a universal bar engaging said printing dies for holding the same in set position and for effecting the impression thereof, spring actuated cam mechanism controlling the successive operation of said universal bars and for rocking said shaft to restore said key-levers, racks and dies to initial position, and a releasable latch for holding said spring mechanism against operation.

90. In a numeral printing and calculating machine, the combination with a set of key-levers, a set of numeral dies and a set of driving racks pivoted respectively to different parts of said key-levers, and a totalizer driven by said racks, the parts of the outer key-levers of the set to which the dies are connected being bent inwardly and ranged close together.

91. In a numeral printing and calculating machine, the combination with the machine frame, of a set of key-levers pivotally mounted within the frame upon a common axis, a set of segmental printing dies and a set of segmental driving racks pivoted to said key-levers on opposite sides of the axis thereof, a totalizer driven by said racks, and means for effecting the impression of said dies, the ends of the outer key-levers to which said dies are pivoted being bent inwardly and ranged close together.

92. In a calculating machine, the combination with a set of totalizer disks and transfer devices between said disks, of a set of driving racks, one for each of said disks, and a set of reversing gears interposed between said racks and said disks.

93. In a calculating machine, the combination with a set of totalizer disks and transfer devices between the disks, of a set of separate, reversible drive mechanisms, one for each of said disks, means for reversing said drive mechanisms, and a set of controlling finger keys, one connected to each of

said drive mechanisms, and arranged to variably shift the same.

94. In a calculating machine, the combination with a set of totalizer disks and transfer devices between said disks, of a set 70 of driving racks, one for each of said disks, a set of reversing gears interposed between said racks and said disks, and a set of finger keys for variably shifting said racks.

95. In a calculating machine, the combination with a set of totalizer disks and transfer devices between the disks, of two sets of oppositely acting drivers, means for connecting the drivers of either set to said totalizer disks, a set of finger keys for variably shifting said drivers, and means for throwing said drivers and said totalizer disks into and out of operative relation and for restoring said drivers while disconnected from said disks.

96. In a calculating machine, the combination with a set of totalizer disks and transfer devices between the disks, of two sets of oppositely acting drivers arranged in pairs, one pair for each of said disks, devices for connecting either set of drivers to said disks, a common shifter for said connecting devices, and a set of fingers, one connected to each pair of drivers, for variably actuating the same.

97. In a calculating machine, the combination with a set of totalizer disks, gears fixed to said disks and transfer devices between said disks, of a set of driving racks, one for each of said disks, a set of reversing 100 gear pinions interposed between said racks and the gears of said disks, a set of finger keys for variably shifting said racks and means for disengaging said racks and for restoring the same and said finger keys to initial position.

98. In a calculating machine, the combination of a set of spur-toothed racks, a totalizer having a set of disks and a corresponding set of spur pinions meshing with 110 said racks, a universal bar for shifting said racks into and out of engagement with said spur pinions, a spring for shifting said universal bar to disengage said racks, and restoring means for said racks normally holding the same in engagement with said pinions against the tension of said spring.

99. In a calculating machine, the combination with a totalizer, of a set of driving racks, a set of reversing gears interposed 120 between said racks and said totalizer, finger key mechanism for variably shifting said racks, and means for throwing said racks into and out of operation and for restoring the same to initial position substantially as 125 described.

100. In a calculating machine, the combination with a totalizer comprising a set of counter wheels each having a spur-toothed pinion, of a set of spur-toothed driving 130

racks, a set of spur-toothed reversing gears interposed between said racks and the counter wheels of said totalizer, finger key mechanism for variably shifting said racks 5 and means for throwing said racks and said totalizer into and out of operative relation and for restoring said racks and key mechanism to initial position, substantially as described.

101. In a calculating machine, the combination with a set of totalizer disks and transfer devices between said disks, of a set of driving racks, finger key mechanism for shifting said racks, a set of pinions meshing 15 with said racks and a set of reversing gears arranged to alternately connect said set of racks and said set of pinions to said totalizer disks, substantially as described.

102. In a calculating machine, the combination with a set of totalizer disks and transfer devices between said disks, of a set 20 of driving racks, finger key mechanism for shifting said racks, a set of pinions meshing with said racks, finger key mechanism for 25 variably shifting said racks, a set of reversing transmission gears, said transmission gears being arranged in pairs with one pair between each disk and the driving rack and pinion therefor and the gears of 30 each pair having a one-way, yielding connection, said set of transmission gears being axially shiftable and arranged to alternately connect the corresponding totalizer disk with the corresponding rack or pinion, substantially as described.

103. In a calculating machine, the combination with a set of totalizer disks and transfer devices between said disks, of a set 40 of drivers, one for each of said disks, each of said drivers having two racks, a set of pinions each meshing with one of the racks of the corresponding driver and a set of reversing transmission gears arranged to alternately connect said pinions and the other 45 racks of the drivers to said totalizer disks, substantially as described.

104. In a calculating machine, the combination with a set of totalizer disks and transfer devices between said disks, of a set 50 of drivers, finger key mechanism for variably operating said drivers, each of said drivers having two racks with the teeth thereof staggered, a set of pinions each meshing with one of the racks of the corresponding driver, and a set of axially shiftable reversing gears arranged to alternately connect said pinions and the other racks of 55 said drivers to said totalizer disks, substantially as described.

105. In a calculating machine, the combi-

nation with a totalizer, a set of drivers for said totalizer, a corresponding set of key levers for variably shifting said drivers, a series of detent arms pivoted to said key levers, springs interposed between said levers and said detent arms and a part with which said detent arms engage to hold said key levers and drivers in set position, substantially as described.

106. In a calculating machine, the combination with a totalizer, of a set of pivoted key levers, segmental drivers connected to said key levers and arranged to operate said totalizer, a series of segmental detent arms pivoted to said key levers, springs interposed between said arms and said levers, said levers having stops with which said arms engage, a part adapted to be engaged by said detent arms to hold said key levers in set position and means for throwing said drivers into and out of operation and for restoring the same and said key levers to initial position, substantially as described.

107. In a calculating and printing machine, the combination with a totalizer, of a set of key levers controlling said totalizer, a set of printing dies pivoted to said key levers, springs interposed between said dies and levers, and a part for holding said dies and levers in set position, said dies having notched edges arranged to engage said part, substantially as described.

108. In a calculating and printing machine, the combination with a totalizer, of a set of pivoted key levers, drivers for said 95 totalizer operated by said key levers, a set of segmental printing dies pivoted to said key levers, springs interposed between said dies and said key levers, said levers having stops against which said dies are normally held 100 by said springs, a universal bar extending over said dies, said dies having notches with which said universal bar engages to hold the same and said key levers in set position, and means for operating said bar to effect 105 the impression of said dies, substantially as described.

109. In a calculating machine, a totalizer comprising driven numeral wheels, carry-over gearing therefor, and ratchet driving 110 mechanism for each numeral wheel comprising a pair of co-acting ratchet gears, one ratchet gear of each pair having driving relation with its numeral wheel and being in driven relation with its co-acting gear 115 when the totalizer is to be operated.
